UNITED STATES PATENT OFFICE.

THEODORE W. FOSTER, OF PROVIDENCE, RHODE ISLAND.

DESIGN FOR AN EAR-RING.

SPECIFICATION forming part of Design No. 15,532, dated November 11, 1884.

Application filed July 31, 1884. Term of patent 7 years.

To all whom it may concern:

Be it known that I, THEODORE W. FOSTER, a citizen of the United States, residing at Providence, in the State of Rhode Island, have invented and produced a new and original Design for an Ear-Ring, of which the following is a specification, reference being had to the accompanying drawings, forming a part thereof.

Figure 1 is a front view of my newly-designed ear-ring. Fig. 2 is an edge elevation of the same.

The leading feature of my design consists in a represented eating-plate crossed by an eat-

ing implement, which may be either a spoon, fork, or table-knife.

In the accompanying drawings, A represents the plate in proper hollowed form, and crossed by an eating implement, B.

I claim—

The design for an ear-ring herein shown and described, the same consisting of the represented eating-plate and eating implement.

THEODORE W. FOSTER.
